[57] CLAIM

The ornamental design for a wind power generator, as shown and described.

DESCRIPTION

FIG. 1 is a perspective view of a wind power generator showing my new design. For clarity of illustration, vanes on the opposite side are not completely shown; FIG. 2 is a typical side elevational view thereof. For clarity of illustration, vanes on the opposite side are not completely shown; and, FIG. 3 is an end elevational view thereof, the end opposite being a mirror image of the end shown in FIG. 3.

FIG. 1

FIG. 2

FIG. 3
